UNITED STATES PATENT OFFICE.

JOHN BIGELOW, OF PHILADELPHIA, PENNSYLVANIA.

MACHINE FOR SEWING AND TRIMMING FABRICS.

SPECIFICATION forming part of Letters Patent No. 244,533, dated July 19, 1881.

Application filed August 19, 1880. (Model.)

To all whom it may concern:

Be it known that I, JOHN BIGELOW, a citizen of the United States, residing at Philadelphia, in the county of Philadelphia and State of Pennsylvania, have invented certain new and useful Improvements in Zigzag or Irregular Stitch Sewing-Machines with Trimming Devices; and I do hereby declare the following to be a full, clear, and exact description 5 of the invention, such as will enable others skilled in the art to which it appertains to make and use the same, reference being had to the accompanying drawings, and to letters or figures of reference marked thereon, which 10 form a part of this specification.

In the accompanying drawings similar letters of reference indicate like parts.

Figure 1 shows a top view of the work-plate of a sewing-machine, with a supplemental work-plate and its actuating device; also a trimming device. Fig. 2 shows, in section, one side of the trimming device, also the actuating device for the supplemental plate. Fig. 3 shows, in section, the supplemental plate, the feed, feed-block, and actuating device for the trimmer. Fig. 4 shows a top view of the feed-block, with the groove in which the feed-dog slides; also the actuating pin of the trimmer. Fig. 5 shows top and sectional views of the feed-dog and its pivotal pin.

The object of the present invention is to produce a combination of mechanism swinging on a pivotal point adapted for a high rate of speed, and, among other things, to make the 35 "cut-hose" patented in Reissue Letters Patent No. 9,113, dated March 9, 1880.

For the purpose of illustration, I have shown my invention applied to the mechanism of the sewing-machine known as the "Willcox & 40 Gibbs."

On the regular plate B of the machine I place a supplemental plate A, Figs. 1, 2, and 3, which is pivoted on B at T. The plate A, at the point where, in sewing, the needle passes through it, is fitted with a tongue, A', arranged to project behind the needle, yet with the necessary clearance, so that the needle can make its stitch alternately on one and the other side of it, and the stitches thus made can, as 45 the work is fed along, be freed from the same without dragging. Beneath this tongue is the

regular throat of the machine, to prevent the loop from being drawn out of line with the looping device.

The knife-plate J, supporting a shear-trimmer, is adjustably attached to the plate A, as shown in Fig. 1, so that the cutting-point S of the shears shall be on a line just behind the end of the tongue A', and will follow the movements of the plate at that point. The 55 opposite end of the shears N is near or over the pivotal point T, and has little or no vibration. This allows the upper shear-blade to be actuated the same as though it were stationary—that is, without lateral movement—and 60 by the device especially set forth in my other application of even date herewith, having serial number 15,651—viz., the lever O pivoted at O', and actuated at P by the pin in the feed-block R.

Since the feed-dog R⁴ engages with and so is obliged to conform to the vibrations of the plate A, a change of construction in the feed mechanism is required—viz., the feed-dog R⁴ is mounted on a slide, R², and attached to the 70 same by a pin, R³, which allows it to swing a little if required. The slide R² is fitted in a groove, R', cut at right angles to the line of feed in the feed-block R. By this arrangement the feed-dog R⁴ can fit closely in the 75 plate A, and yet follow it in the vibrations necessary to make the zigzag stitch. Where the lateral vibration is very slight the pivotal pin R³ is not essential.

On the main shaft of the machine is a small 85 gear, W, which meshes into a gear, H, double its size—that is, having two teeth to one of the other—carrying a cam. In this cam a lever, pivoted to the frame of the machine at G³, engages by means of the pin G. A link is 90 connected to this lever at G', and at G² to the under side of the plate A.

In operation the cam attached to the gear H vibrates, through the pin G, the lever pivoted at G³. This, by means of the link which 95 connects with it at G' and with the plate at G², conveys its motion to the said plate A, and causes the tongue A' on said plate to move alternately to the right and left of the point of perforation of the needle, and since the feed 100 conforms to the lateral movements of the plate A the work is moved in an irregular course,

causing the stitching to be zigzag. The cutting-point S of the shears, which are closed when the needle is in the work and open when the feed takes place, trims the edge at any required distance from the sewing, thus making the seam mentioned in the cut-hose patent referred to in the beginning of this specification.

The foregoing specification and accompanying drawings show the vibrating tongue and a trimming device as applied to a Wilcox & Gibbs sewing-machine; but by slight modifications of the mechanism, essentially the same, however, in principle, they can equally well be applied to any of the sewing-machines now in use, such as the Singer, Wheeler & Wilson, Grover & Baker, and others having a stitch-forming mechanism, which consists of a needle, feed, presser-foot, work-plate, needle-throat, and looper or shuttle.

I am aware that a vibrating plate and tongue above the presser-foot have been used; but such will not produce the zigzag stitch.

What I claim, and desire to secure by Letters Patent, is—

1. In combination with the stitch-forming mechanism of a sewing-machine, a swinging plate arranged under the presser-foot and pivoted behind the needle and provided with a tongue, substantially as and for the purposes set forth.

2. In combination with the stitch-forming mechanism of a sewing-machine, the tongue A', suitably attached to a tongue-plate, A, and feed-dog R⁴ arranged to swing in an arc across the line of feed, substantially as described.

3. In combination with the stitch-forming mechanism of a sewing-machine, a tongue, A', suitably attached to a tongue-plate, A, feed-dog R⁴, and a shear-trimmer attached to and moving with a swinging work-plate pivoted behind the sewing mechanism, substantially as described.

In testimony whereof I affix my signature in presence of two witnesses.

JOHN BIGELOW.
